JOSEPH POISSON, OF FALL RIVER, MASSACHUSETTS, ASSIGNEE TO DRAPER COMPANY,
OF HOPEDALE, MASSACHUSETTS, A CORPORATION OF MAINE.

TENSION FOR LOOM-SHUTTLES.

1,138,310.

Specification of Letters Patent.

Patented May 4, 1915.

Application filed January 22, 1914. Serial No. 513,769.

To all whom it may concern:

Be it known that I, JOSEPH POISSON, of Fall River, in the county of Bristol, and State of Massachusetts, have invented a new and Improved Tension for Loom-Shuttles, of which the following is a specification.

The improved tension devices are illustrated in the accompanying drawings, wherein—

- 10 Figure 1, is a plan view of the eye end of the shuttle equipped with the present improvements, parts being broken away to facilitate the illustration. Fig. 2, is a vertical section in the plane indicated by the line 2—2 in Fig. 1. Fig. 3, is a rear view of the automatic threader, a portion being broken away. Fig. 4, is a horizontal section in the plane indicated by the line 4—4 in Fig. 2. Fig. 5, is a side view on an enlarged 20 scale of the roughened tension snubbing posts at the eye of the shuttle. Fig. 6, is a horizontal section on a still larger scale of one of the roughened tension snubbing posts. Fig. 7, is a side view on the same scale as Fig. 6, of a portion of one of the roughened tension snubbing posts. Figs. 8 and 9, are still further magnified detailed views illustrating the manner in which the roughened surfaces of the snubbing posts are produced. 30 The improvements are illustrated in connection with an automatically threading loom shuttle having an automatic threader of the character shown in United States Letters Patent of William F. Draper, No. 834,607, October 30, 1906. As in that patent, the shuttle has a side eye A having an open slot a at its top through which the thread is received. The automatic threader B has a longitudinal thread passage C communicating at its front end with the side eye and at its rear end with the weft holding chamber D of the shuttle. This thread passage is overhung by thread retaining guards of customary character as shown at b, b, in the drawings, these guards being arranged in customary manner so as to provide a tortuous threading slot c for the entrance of the thread into the thread passage C. In all of these respects the drawings illustrate 40 a well-known automatically threading shuttle such as is frequently used in weft replenishing looms of the well-known Northrop or Draper type, typified, for example, by the United States Letters Patent of James H.

Northrop, No. 529,940, November 27, 1894. It is to such a well-known shuttle that the present improvements are applied.

The shuttle is provided with three snubbing posts, E, F, and G, as best shown in Fig. 4. The two snubbing posts F, and G, are at opposite sides of the side eye A while the third snubbing post, E, is at the juncture between the thread passage C and the side eye A. When the shuttle is running in the direction indicated by the arrow in Fig. 4, the thread passes around the post E and advances in contact with the post F as indicated by full lines in Fig. 4. When the shuttle is traveling in the opposite direction the thread passes from the post E around the post G as indicated by dotted lines in Fig. 4. The post E is so located that its surfaces is tangential to a lateral plane which passes midway between the two posts F and G so that the tension on the thread is substantially the same which ever way the shuttle is running.

In addition to serving the usual function of preventing the thread cutting into the wood of the shuttle as it reeves through the eye the snubbing posts F and G are roughened so as to apply tension to the thread. This roughening of the snubbing posts is of peculiar character as best illustrated in Figs. 6, 7, 8, and 9. Each snubbing post F and G is of hard steel and is formed with parallel spiral threads d. After these spiral threads d are formed they are roughened by notches e cut across the tops of the threads. These notches are likewise spirally arranged but their spiral disposition is in opposite direction to that of the screw threads as illustrated in Figs. 5, 7 and 9. Accordingly, as is apparent from a consideration of Fig. 7, when a thread reeves around one of the roughened snubbing posts in a substantially horizontal plane, it encounters several of the spiral threads and likewise several of the notches, so that tension is effectively applied. Each thread has numerous small projecting filaments which are engaged by the roughening threads, as indicated in Fig. 6, thereby contributing to the tension effect.

The two posts F and G have their spirals running in opposite directions as illustrated in Fig. 5. This is useful in connection with the slotted side eye since, which ever way the shuttle is running, the thread tends to

run down the post toward the bottom of the thread eye thus keeping the thread away from the open slot of the eye and contributing in holding the thread from jumping out of the open slot. A similarly constructed tension post H is located at the entrance to the longitudinal thread passage C as illustrated in Figs. 3 and 4. This tension post H extends across the bottom of the thread passage C and contributes in applying tension. The spiral threads of this post tend to work the thread against the rear wall of the thread passage C, as shown in Fig. 4, beneath the rear overhang b thereby aiding in preventing the upward escape of the thread out through the threading slot C.

By reason of the spiral threads, each tension post presents a series of grooves and angular ribs extending diagonally to the path of the yarn as it reeves around the post, and each diagonal rib is itself roughened by serrations. Consequently, each yarn as it is delivered from the shuttle drags over the roughened edges of several diagonal ribs so that the requisite tension is thereby imparted to the yarn.

I claim—

1. A loom shuttle having, in combination, a slotted side eye; an automatic threader 30 with a longitudinal thread passage communicating at its front with the side eye and at its rear with the weft chamber of the shuttle; two vertical snubbing posts at opposite sides of the thread eye; a snubbing post at 35 the juncture between the longitudinal thread passage and the side eye with its front face in a lateral plane passing midway between the snubbing posts at opposite sides of the side eye; a horizontal tension post at the 40 bottom and entrance of the longitudinal thread passage, said tension post, and each of the snubbing posts at the side eye being roughened by means of spiral threads and cross-wise extending notches at the tops of 45 said threads, and the spiral threads of the snubbing posts at the sides of the side eye being disposed in opposite directions and in such direction as to tend to feed the thread down toward the bottom of the side eye..

2. A loom shuttle having, in combination, a slotted side eye; an automatic threader with a longitudinal thread passage communicating at its front with the side eye and at its rear with the weft chamber of 55 the shuttle; two vertical snubbing posts at opposite sides of the thread eye; a snubbing post at the juncture between the longitudinal thread passage and the side eye; a horizontal tension post at the bottom and entrance of the longitudinal thread passage, said tension post, and each of the snubbing posts at the side eye being roughened by means of spiral threads and cross-wise extending notches at the tops of said threads, 60 and the spiral threads of the snubbing posts

at the sides of the side eye being disposed in opposite directions and in such direction as to tend to feed the thread down toward the bottom of the side eye.

3. A loom shuttle having, in combination, 70 a side eye; a longitudinal thread passage communicating at its front with the side eye and at its rear with the weft chamber of the shuttle; two vertical snubbing posts at opposite sides of the thread eye; a snubbing post at the juncture between the longitudinal thread passage and the side eye; a horizontal tension post at the bottom and entrance of the longitudinal thread passage, 75 said tension post, and each of the snubbing posts at the side eye being roughened by means of spiral threads; and cross-wise extending notches at the tops of said threads.

4. A loom shuttle having, in combination, 80 a slotted side eye; an automatic threader with a longitudinal thread passage communicating at its front with the side eye and at its rear with the weft chamber of the shuttle; two vertical snubbing posts at 85 opposite sides of the thread eye; and a snubbing post at the juncture between the longitudinal thread passage and the side eye, each of the snubbing posts at the side eye being roughened by means of spiral threads and cross-wise extending notches at the tops of 90 said threads, and the spiral threads of the posts at the sides of the eye being disposed in opposite directions and in such direction as to tend to feed the thread down toward 95 the bottom of the side eye.

5. A loom shuttle having, in combination, 100 a side eye; a longitudinal thread passage communicating at its front with the side eye and at its rear with the weft chamber of the shuttle; two vertical snubbing posts at opposite sides of the thread eye; and a snubbing post at the juncture between the longitudinal thread passage and the side eye, and each of the snubbing posts at the side eye being roughened by means of spiral threads 105 and cross-wise extending notches at the top of said threads.

6. A loom shuttle having, in combination, 110 a slotted side eye; and two snubbing posts at opposite sides of the thread eye; each of the snubbing posts at the side eye being roughened by means of spiral threads, and the spiral threads of the two posts being disposed in opposite directions and in such direction as to tend to feed the thread down 115 toward the bottom of the side eye.

7. A loom shuttle having, in combination, 120 a side eye; a longitudinal thread passage communicating at its front with the side eye and at its rear with the weft chamber of the shuttle; two roughened vertical snubbing posts at opposite sides of the thread eye; and a snubbing post at the juncture between the longitudinal thread passage and the side eye.

8. A loom shuttle having, in combination, a side eye; and two roughened snubbing posts at opposite sides of the thread eye.
9. A loom shuttle having, in combination, a slotted side eye; an automatic slotted threader with overhanging guards and a longitudinal thread passage communicating at its front with the side eye and at its rear with the weft chamber of the shuttle; and a horizontal tension post at the bottom and entrance of the longitudinal thread passage, said tension post being roughened by means of spiral threads so arranged as to force the yarn against the side wall of the thread passage, thereby aiding in preventing the escape of the yarn through the threading slot.
10. A loom shuttle having, in combination, a side eye; a longitudinal thread passage communicating at its front with the side eye and at its rear with the weft chamber of the shuttle; and a horizontal tension post at the bottom and entrance of the longitudinal thread passage, said tension post being roughened by means of spiral threads and cross-wise extending notches at the tops of said threads.
11. A loom shuttle having a roughened tension post with spiral threads and notches

cut across said threads, the notches themselves being spirally disposed, the spiral of the notches being in opposite direction to the spiral of the threads.

12. A loom shuttle having a roughened tension post with spiral threads and notches cut across said threads, the notches themselves being spirally disposed.

13. A loom shuttle having a roughened tension post with spiral threads and notches cut across said threads.

14. A loom shuttle having a roughened tension post with spiral threads.

15. A loom shuttle having a roughened tension post with a series of ribs extending diagonally to the path of the yarn as it reeves around the post, each rib being serrated at its edge.

16. A loom shuttle having a roughened tension post having a series of ribs extending diagonally to the path of the yarn as it reeves around the post.

In witness whereof I have hereunto signed my name in the presence of two subscribing witnesses.

JOSEPH POISSON.
